INVENTOR.

Jesse McComas
By Robert A. Meiss
Attorney.

UNITED STATES PATENT OFFICE.

JESSE McCOMAS, OF LOS ANGELES, CALIFORNIA.

TELEPHONE INDEX.

Application filed March 27, 1924. Serial No. 702,407.

To all whom it may concern:

Be it known that I, JESSE McCOMAS, a citizen of the United States, and a resident of Los Angeles, in the county of Los Angeles and State of California, have invented new and useful Improvements in Telephone Indexes, of which the following is a specification.

This invention relates to telephone indexes and more particularly to a form of index adapted to be applied to a telephone transmitter and consisting of a metallic body adapted to be clamped between the telephone transmitter and the mouthpiece, so as to be held in convenient position for the user of the telephone, and provided with a plurality of tabs and cards upon which information and advertisements may be printed, together with a conveniently arranged index of names and telephone numbers in alphabetical order.

Other objects may appear as the description of my invention progresses.

In the accompanying drawings I have shown a preferred embodiment of my device, subject to modification within the scope of the appended claims without departing from the spirit of my invention.

In said drawings:

Fig. 1 is a face view of a telephone with my improved index mounted thereon in position for use.

Fig. 2 is a side elevation of the same.

Fig. 3 is a perspective view of the index holder.

My improved device includes a holder R formed of a single piece of thin sheet metal, adapted to be stamped or pressed into the form shown in Fig. 3, held on a telephone in the position shown in Figs. 1 and 2. The holder includes a main base portion 1 with a right angularly extended arm 2 which has a semi-circular cut 3 in the end thereof arranged to fit under the outer portion of the mouthpiece M, and over the extended portion e of the face f of a telephone transmitter R, so that when the mouthpiece M is tightly screwed into place on the transmitter R the portion 2 of the holder will be firmly held between the portion e of the transmitter and the inner shoulder of the mouthpiece M. When the holder is properly positioned on the telephone, the portion 2 is preferably horizontally disposed, while the portion 1 is vertically disposed.

A plurality of elongated vertical cuts 4,

4, etc., are formed in the portion 1 of the holder by means of dies or otherwise, so that the material cut from the portion 1 may be formed into clips as at 5, 5, etc., which are first formed into loops 6, 6, etc., extending forwardly from the front surface of the holder and thence rearwardly as at 7, 7, etc., to a point substantially in the plane of the portion 1 of the holder, and thence upwardly as at 8, 8, etc., in the plane of said portion 1.

The clips 5, 5, etc., are so formed that the portions 7, 7, etc., thereof are substantially spaced from the upper edge 9 of the holder.

The holder as shown and described is adapted to removably hold in position a plurality of index cards or tabs as at 10, 10, etc., which have a width substantially corresponding to the portion 1 of the holder, and between which sheets of paper of suitable thickness may be held for carrying the names and telephone numbers, the character or form of these sheets being immaterial to my invention.

The index cards 10, however, and the sheets held therebetween are provided with apertures 11, 11, etc., near the upper edges which are spaced to correspond to and are adapted to receive the clips 5 of the holder.

As shown in Fig. 1, the index cards 10 vary in length and are preferably arranged so that the outermost card is substantially of the length of the portion 1 of the holder, while the inner cards are of successively greater length, so that a narrow portion of each of the index cards will be visible from the front of the device for providing an alphabetical index and for listing certain information which appears on the interior of the index in sheets held therebetween. This is clearly illustrated in Fig. 1, and it will be observed by reference thereto that advertisements may be conveniently arranged on the front faces of the cards 10, while information relating to domestic and foreign postage, money order rates, calendars and other information may be placed on the backs of said cards, which will be visible when the cards are turned upwardly, as indicated by broken lines in Fig. 2. Also, the cards are adapted to be turned upwardly for rendering a desired card index of telephone numbers visible, as indicated by the alphabetical notations on the lower ends of the cards 10.

The form of the clips 5 is such that when

one or more of the cards and sheets are turned upwardly, as shown in Fig. 2, the cards will be held in a rearwardly inclined plane by means of the engagement of the

5 upper edges 9 of the cards with the inner sides of the portions 6 of clips 5, while lower portions of the cards will rest against the upstanding portions 8 of said clips.

To the end that suitable numbers of the 10 cards 10 and information sheets may be thus held, the loops 6 are extended upwardly of the face of the holder for a distance corresponding to the sum of the thicknesses of the cards 10 and sheets held therebetween, 15 so that the cards may rest upon the horizontal portions 7 of the clips and against the portions 6 and 8 thereof.

It will be understood that the telephone transmitters R are usually mounted on a 20 suitable stand S in the case of desk telephones, and on boxes in the case of wall telephones, but in all events the transmitters R are extended sufficiently so that there is ample room for the index and holder shown in 25 the drawings and described herein.

It will also be understood that the character of the telephone transmitters R and mouthpieces M differ in many cases, and I may modify or change the form of the arm 30 2 of the holder and the cut 3 in the end thereof so as to conform to and adapted to be firmly held on the face f or the portion e of a transmitter R.

It will be observed that I have provided 35 a compact, convenient and economical form of index which is readily attachable to and detachable from an ordinary telephone transmitter without injuring the same or interfering with the use thereof, and the 40 holder H being made of sheet metal affords a substantially rigid surface whereby notations may be made on the sheets between the index cards during the progress of a telephone communication.

45 What I claim is:

1. A telephone index including a holder 50 integrally formed of sheet metal and having a vertically extended portion and a horizontally extended portion formed in the same plane, said horizontal portion being adapted for attachment to a telephone transmitter, and said vertical portion having elongated 55 cuts made therein with the material from said cuts formed into narrow strips and bent upwardly and thence forwardly and rear-

wardly, forming loops and supporting portions for holding a plurality of index cards in operative and inoperative position thereon.

2. A telephone index comprising a holder 60 integrally formed of sheet metal and adapted for attachment to a telephone transmitter, said holder having clips formed therefrom and extended forwardly thereof, and thence rearwardly and upwardly, said 65 rearwardly extended portions being substantially spaced from the upper edge of the holder, as and for the purpose described.

3. A telephone index comprising a holder 70 integrally formed of sheet metal and adapted for attachment to a telephone transmitter, said holder having clips formed therefrom and extended forwardly thereof, and thence rearwardly and upwardly, said 75 rearwardly extended portions being substantially spaced from the upper edge of the holder, and a plurality of index cards arranged to hold sheets of paper therebetween and carried on said clips.

4. A telephone index comprising a holder 80 integrally formed of sheet metal and adapted for attachment to a telephone transmitter, said holder having clips formed therefrom and extended forwardly thereof, and thence rearwardly and upwardly, said 85 rearwardly extended portions being substantially spaced from the upper edge of the holder, and a plurality of index cards arranged to hold sheets of paper therebetween and carried on said clips, the lower portions 90 of said clips serving to hold said cards and said sheets in inoperative position, and the upper portions of said clips serving to hold the same in operative position.

5. A telephone index including a holder 95 formed of flat sheet metal and provided with a semi-circular cut in one edge thereof, whereby said holder may be clamped between the telephone transmitter and mouth-piece, means for supporting a plurality of 100 index cards on the upper portion of said holder, said means being arranged for holding said cards in position above the holder for rendering the inner sides of said cards visible for use.

JESSE McCOMAS.
